(57) **CLAIM**

The ornamental design for an armrest organizer for a compact disc player and accessories, as shown and described.

DESCRIPTION

FIG. 1 is a front perspective view of an armrest organizer for a compact disc player and accessories, shown in an open position with environment, the broken lines forming no part of my claimed design;

FIG. 2 is a front elevation view of the invention illustrated in FIG. 1, but shown in a closed position;

FIG. 3 is a rear elevation view thereof;

FIG. 4 is a right elevation view thereof;

FIG. 5 is a left elevation view thereof;

FIG. 6 is a top plan view thereof; and,

FIG. 7 is a bottom plan view thereof.
